GRINDING APPARATUS

Alfred E. Hamilton, Pittsburgh, Pa.

Application March 23, 1946, Serial No. 656,725

6 Claims. (Cl. 51—192)

1

My invention relates to grinding rolls for the surfacing of metal, wood, etc., and more particularly to rolls having drums of the pneumatic type that contain the abrasive or surfacing material on their peripheral faces.

Grinding apparatus of this type frequently comprises one grinding roll or a pair of grinding rolls for surfacing strips or sheets of material, each roll having a metal hub mounted on a shaft and a pneumatic drum mounted on the hub and carrying the abrasive material, the abrasive material being contained on sleeves or on spirally-wound strips that surround the drum.

My invention has for its object the provision of apparatus of the character referred to, wherein pneumatic pressure is maintained at a desired predetermined degree, not only to provide the required or desired resistance by the pneumatic drum to grinding pressures, but which pressure is also utilized to releasably maintain the drum on its hub and to hold the abrasive strips in place on the drum.

In the accompanying drawing, Figure 1 is a view partly in section and partly in elevation showing a pair of rolls embodying my invention, and Fig. 2 is an enlarged sectional view through a portion of a pneumatic drum and its hub.

The numerals 4 indicate the roll stand on which a pair of rolls 5 and 6 are supported by their respective shafts 7 and 8, the shafts being driven from a suitable source of power, by pulleys 9 and 10. As here shown, the rolls 5—6 are of identical construction and will grind or surface both sides of a strip or sheet that is passed between them. It will be understood that when only one face of a sheet is to be surfaced, a plain-faced billy roll can be substituted for the roll 6.

Since the rolls 5 and 6 are of identical construction, a description of the roll 5 will suffice for both rolls. This roll 5 comprises a hollow hub portion 11 of cylindrical contour whose end walls or plates are welded or otherwise secured to the shaft 7. Circular stiffening discs 12 are welded to the shaft 7 and to the inner peripheral surface of the hub, to stiffen the hub and permit the use of thinner gage metal for the hub.

A pneumatic drum 14 of rubber or other suitable elastic material is carried on the drum and has radially-spaced walls 15 and 16 that are joined at their ends, to provide a closed chamber 32 for the retention of air pressure within the drum. Helical strips 17 of tough paper or cloth and having grit particles adhesively secured to their exposed surfaces are wound helically on the drum 14, their ends being suitably secured in

place thereon. In the present instance, the strip ends are folded back as indicated at 19, the back-turned ends being disposed between the hub and the innermost peripheral surface of the drum and held there by reason of the air pressure in the drum. The helical turns of the strips are spaced apart perhaps one inch, at 21 to permit of some slight expansion or bulging of the drum at those areas (Fig. 2) and to thereby hold the strips 5 against displacement axially of the drum. Also, the peripheral wall of the hub 11 is grooved as shown at 22 so as to provide an annular depression into which the drum will be expanded under its internal air pressure. This is for the purpose of preventing endwise shifting of the drum on the hub and thus avoid the necessity of providing end plates or flanges on the ends of the hub to hold the drum in place thereon.

A constant supply of air pressure is maintained 20 within the drum for the purpose of giving a desired resistance for grinding pressure and also to retain the strips in place on the drum and to maintain the proper spacing between the helical turns. The pressure-supply system comprises a 25 reservoir 23 to which air under pressure is supplied by a pipe 24 leading from a suitable compressor or pump. Air from the reservoir flows through a pressure-regulating valve 25 and past a relief valve 26, and through a pipe 27 which 30 leads through a rotary joint or swivel coupling 28 into a bore in the shaft, and thence through a pipe 29 and a coupling 31 into the chamber 32 of the drum 14. The rotary coupling at 28 permits of maintaining a constant supply of air 35 pressure during rotation of the roll.

The pressure regulator 25 is adjusted to give the desired pressure in the pneumatic drum, while the relief valve 26 is adjusted to permit of 40 exhaust of pressure from the drum in case the air therein is expanded to a pressure above that desired in the drum, which expansion may take place because of increase in atmospheric temperature, or may result from the heat of grinding friction. A similar pressure supply and relief system is provided for the roll 6, the pressure-regulating valve being shown at 33 and the pressure-relief valve at 34, the air being conducted to the lower drum through a pipe 35. Where it is desired to have identical pressures in the upper 45 and lower drums, a valve 36 in the line 39 will be closed and a valve 37 in a cross-connecting line 38 will be open, the pressure regulator 25 in that case serving for both drums.

In setting up the apparatus for a surfacing 55 operation, the pneumatic drums are placed on

their respective hubs and connected to their respective supply pipes by the couplings 31 and the abrasive strips wound on the drums and their ends folded back and tucked in between the drum and the hub. Thereupon, air pressure will be admitted to the air drums to effect expansion thereof at 21 and 22 and to give the desired degree of "hardness" or resistance to the drums.

It will be understood that instead of using a plurality of abrasive strips on each drum, a single strip would suffice, if made of adequate width and wrapped the required number of turns on the drum and with the proper helical pitch spacing.

I claim as my invention:

1. A grinding roll comprising a hub, a flexibly-walled drum on the hub, containing an abrasive and having radially-spaced walls and end walls forming an annular-closed chamber, a depressed area in the periphery of the hub, and means for supplying air under pressure, to the interior of the drum, for expanding the innermost peripheral wall thereof into the said area.

2. A grinding roll comprising a hub, a flexibly-walled drum on the hub, containing an abrasive and having radially-spaced walls and end walls forming an annular-closed chamber, a radially-offset area at the periphery of the hub, and means for supplying air under pressure, to the interior of the drum, for expanding the innermost peripheral wall thereof into the said area, the said offset area being in the form of an annular groove in the periphery of the hub, intermediate the ends thereof.

3. A grinding roll comprising a hub, a flexibly-walled drum on the hub, having radially-spaced walls and end walls forming an annular-closed chamber, an abrasive-containing strip wrapped helically on the periphery of the drum, with its successive turns in spaced-apart relation, and means for supplying air under pressure to the interior of the drum, for expanding the outermost peripheral wall of the drum into the spaces between said helical turns.

4. A grinding roll comprising a hub, a flexibly-walled drum on the hub, having radially-spaced walls and end walls forming an annular-closed

chamber, an abrasive-containing strip wrapped helically on the periphery of the drum, with its successive turns in spaced-apart relation, means for supplying air under pressure to the interior of the drum, for expanding the outermost peripheral wall of the drum into the spaces between said helical turns, and means acted upon by said pressure, for gripping the ends of the strips to hold them in place against the drum.

5. A grinding roll comprising a hub, a flexibly-walled drum on the hub, having radially-spaced walls and end walls forming an annular-closed chamber, an abrasive-containing strip wrapped helically on the periphery of the drum, with its successive turns in spaced-apart relation, and means for supplying air under pressure to the interior of the drum, for expanding the outermost peripheral wall of the drum into the spaces between said helical turns, the ends of the strips being folded back between the drum and the hub, whereby they are held in place by said air pressure.

6. A grinding roll comprising a hub, a drum of elastic material carried by and surrounding the hub, a shouldered area on the peripheral surface of the drum, an abrasive-containing strip wrapped helically on the periphery of the drum, with its successive turns in spaced-apart relation, and means for supplying air under pressure, to the interior of the drum, for expanding the innermost and outermost walls of the drum, into engagement with said shouldered area and into the spaces between said helical turns, respectively.

35 ALFRED E. HAMILTON.
